UNITED STATES PATENT OFFICE.

CHARLES L. KRUM AND HOWARD L. KRUM, OF CHICAGO, ILLINOIS, ASSIGNEES, BY
MESNE ASSIGNMENTS, TO MOKKRUM-KLEINSCHMIDT CORPORATION, OF CHICAGO,
ILLINOIS, A CORPORATION OF DELAWARE.

PRINTING OR SELECTING TELEGRAPHS.

Application filed December 23, 1919, Serial No. 346,948. Renewed October 30, 1926.

The invention relates to printing or selecting telegraphs and seeks to provide an improved system and apparatus which is accurate and rapid in operation and in which 5 the apparatus at the different stations can be readily maintained in proper working condition.

To this end the invention provides improved transmitting and receiving apparatus 10 having sets of permutation members or selectors corresponding in number to the selecting units of a definite interval code, and in which electric contacts and magnets are reduced to a minimum the operations, for 15 the most part, being effected mechanically rather than electrically. A further object of the invention is to provide improved apparatus in which the receiver is kept in proper timed relation with the signals by initiating 20 the operation of the rotary receiver shaft in response to a starting unit or interval which precedes the selecting units or intervals of each signal.

The invention consists in the features of 25 improvement hereinafter set forth, illustrated in preferred form and arrangement in the accompanying drawings, and more particularly pointed out in the appended claims.

30 In the drawings—

Figure 1 is a plan view with the brackets which carry the receiver or printer shown in horizontal section;

Fig. 2 is a detail section on the line 2—2 35 of Fig. 1;

Fig. 3 is a vertical section on line 3—3 of Fig. 1 with the motor broken away and illustrating the transmitter;

Fig. 4 is a detail section on the lines 4—4 0 of Figs. 1 and 6;

Fig. 5 is a section on the lines 5—5 of Figs. 1 and 6;

Figs. 6 and 7 are detail sections on the lines 6—6 and 7—7, respectively, of Fig. 1;

Fig. 8 is a rear elevation of the apparatus with the base broken away;

Fig. 9 is a front elevation of the receiver or printer of the apparatus;

Fig. 10 is a vertical section on the line 50 10—10 of Figs. 11 and 12 with the parts shown shifted from normal or zero position;

Fig. 11 is a side elevation of the receiver or printer with the controlling clutch shown in vertical section;

Fig. 12 is a vertical front to rear section of the receiver with parts in the position shown in Fig. 10;

Fig. 13 is a vertical section on the line 13—13 of Fig. 11;

Fig. 14 is a detail section on the line 14—14 of Fig. 12;

Fig. 15 is a detail elevation of the trip mechanism for the receiver clutch with parts shown in shifted position;

Fig. 16 is a development of the cam which controls the operation of the selector-operating shuttle;

Figs. 17 to 20, inclusive, are fragmentary views illustrating modifications of the receiver selecting mechanism;

Figs. 21, 22 and 23 are diagrams of different circuits in which the improved system and apparatus are applicable.

The transmitter and receiver of the improved apparatus are both mounted upon a common base 1 and are operated by a common motor 2. The operation of the receiver is controlled by a magnet 3 and, in the preferred form shown the operation of the transmitter is controlled by a keyboard. A small electric motor 2 is preferably employed and, for convenience in assembling, is mounted on a base 4 removably fixed to a plate 5 that is detachably mounted upon the upper face of the base 1. The motor shaft is provided at its inner end with a fly wheel 6 and its outer end is connected by a pair of beveled gears 7 to a fly ball governor 8. The latter is connected to a movable contact 9 that is normally held by a spring 10 in engagement with an adjustable contact 11. The motor circuit extends through the contacts 9 and 10 and, by shifting the movable contact, the governor maintains the speed of the motor at the desired uniform rate. The spring 10 is connected to an adjusting screw 12 for regulating its tension and by adjusting this screw and the contact 11 the desired rate of speed for the motor can be obtained.

The base 1 is a hollow casting and has an extension 13 at its lower front portion. The transmitter keyboard comprises finger keys

14 and a space bar 15. The keys are carried upon the upturned forward ends of a set of levers 16, which are arranged within the upper portion of the base with their forward ends extending outwardly through an opening in the base and over the base extension 13. Front and rear comb bars 17 and 18 are provided for guiding the key levers and the latter are connected to the rear comb bar by a common pivot rod 19. The space bar 15 is mounted on a bail 20 that is pivoted on the upper face of the base extension and engages the downwardly offset forward end of one of the key levers. 10

15. The characters are represented by permutations of two different line conditions extending through a definite number of time intervals or units. Preferably a five interval or five-unit signal code is employed and the 20 signals are represented by permutations either of current and no current or of positive and negative impulses extending through the five time intervals or units of each signal. 25

25. To selectively determine the signals to be transmitted, the key levers are provided with depending fingers 21 which variably operate a set of five bars or bails 22 that extend transversely below the levers. An additional 30 starting bar or bail 23 is provided and is uniformly operated by all of the key levers. These bails are pivoted on comb blocks 24 fixed in position at the sides of the base 1 and U-springs 25 normally uphold the key 35 levers and bails with the key levers engaging a transverse stop portion 26 at the upper front portion of the base, and with the bails engaging the fingers 21. These springs are provided with hooks at their upper ends 40 which engage the key levers and the arms of the bails, and the lower downturned ends of the springs engage openings in a fixed transverse bar 27. The extent of depression of the key levers and bails is limited by a 45 stop 28 fixed to the bar 27 and projecting forwardly beneath the bails.

The bails 22 are provided at their right-hand ends with arms 29 that project upwardly through an opening in the base 1 and are 50 pivoted to the rear ends of a set of five selecting members or fingers 30. The selecting fingers extend forwardly through guiding notches formed in the upper portion of a common transverse bar 31. Bar 31 preferably forms part of the bail 32, which is mounted on a pivot pin or shaft 33. The latter is mounted in rearwardly projecting arms or lugs 34 formed upon an upright bracket 35 that is fixed to the base 1. An 55 upwardly extending arm 36 on the bail carries an insulated contact 37 that is arranged to engage an insulated adjustable contact 38 on the upper end of the bracket 35. These contacts form a transmitter switch and are 60 preferably normally held in engagement by 65

a spring 39 which extends between the lower portion of the bracket and the depending lug on the bail 32.

A set of five switch shifters is provided for operating the movable contact 37. In the 70 form shown, the switch shifters 40 are provided with U-shaped forward ends which pivotally engage the pin or shaft 33 and their rear ends extend through the guiding notches of the bar 31 and rest upon the forward ends 75 of the controlling fingers 30. At their rear ends the switch shifters are provided with beveled shoulders 41 on their lower edges and with raised lugs 42 on their upper edges, and these shoulders and lugs are arranged to be 80 engaged respectively by the beveled forward ends of the selecting fingers 30 and by a set of five cams 43 which are arranged in a helical series on a transmitter actuating shaft 44.

Shaft 44 is journaled in suitable bearings 85 on the bracket parts 34 and is driven from the motor 2 through the medium of suitable connections controlled by a clutch. In the arrangement shown (see Figs. 1, 2 and 7), the clutch is mounted on a short horizontal 90 shaft 45 which extends from front to rear of the machine and is journaled in two brackets 46 and 47 mounted on the base plate 5. A worm wheel 48 is mounted on the rear end 95 of the clutch shaft and engages a worm 48' on the shaft 49 that is continuously driven, when the machine is in operation, by the motor 2. The forward end of the shaft 45 is connected by a pair of beveled gears 50 of equal size to the transmitter shaft 44, or preferably, as shown, to an intermediate shaft 51, which is journaled in the rearwardly projecting lug on the bracket 47 and in a bracket 52 on the base plate 5. The intermediate shaft 51 is in line with the transmitter actuating shaft 44 and is connected thereto by a detachable coupling which preferably comprises two disks, 53 and 54, adjustably fixed 100 by set screws to the respective shafts, and one of which is provided with an eccentric 110 pin 55 engaging a notch in the other disk. The worm shaft 49 is journaled in lugs on bracket 46 in line with the motor shaft and is preferably connected thereto by a similar 115 detachable coupling comprising two disks 56.

The transmitter clutch comprises driving and driven members 57 and 58 having conical working faces (see Fig. 7). The driving clutch member 57 is in the form of a metal cup and is fixed to the hub of the worm wheel 48. The worm wheel and driving member are loose on the shaft 45 and a yoke 59, fixed to the bracket 46, engages a groove in the hub of the worm wheel and holds it and the driving clutch member 120 against axial movement. The driven clutch member 58 is preferably formed of wood and is fixed to a flanged sleeve 60 that is pinned to the clutch shaft 45. This shaft 125 can shift in axial direction to a slight ex- 130

tent through its bearings 61 and 62 and through the hub of the gear 50 thereon. The forward end of the shaft is squared and engages a corresponding bore in the hub of the gear 50 to drive the latter. This axial movement of the shaft 45 serves to engage and disengage the clutch members. The driven clutch member 58 is provided on its outer face with a cone 63 which is arranged to engage the internal face of an annular brake 64 that is carried on the bracket 47 by means of two pairs of screw pins 65 and 66. The screws 65 extend loosely through openings in the bracket and are adjustably threaded into the body of the brake 64. The screws 66 are fixed to the bracket and the rear ends thereof engage guiding openings in the brake (see Fig. 1). Springs 67 coiled about the screw pins 66 yieldingly hold the brake in position with the heads on the outer ends of the screw 65 engaging the outer face of the bracket 47. By means of the screws 65 the position of the brake and the tension of the springs 67 can be adjusted.

A heavy spring 68 coiled about the forward end of the clutch shaft 45 extends between the flanged bearing 62 and the loose washer 69 which bears against the forward end of the flanged sleeve 60. Preferably, anti-friction rollers are interposed between the washer and the sleeve. This spring tends to shift the clutch shaft rearwardly and move the driven clutch member 58 thereon into operative engagement with the driving member 57. In the normal or zero position, however, the shaft is held, by a trip arm or lever 70, in its forward position against the tension of the spring 68 and with the cone 63 of the driven clutch member engaging the brake 64. The trip arm or lever 70 is pivoted at its upper end in a yoke 71 and its lower end engages a guiding yoke 72, both of the yokes being fixed to and projecting rearwardly from the bracket 46. A roller 73, journaled within an opening in the trip lever, engages the rear face of a cam disk 74 that is held by a set screw upon the rear end of the clutch shaft 45 and which is provided with an eccentric lug 75 arranged to co-operate with the roller 73. A locking latch 76 is arranged to engage the lower end of the trip arm 70. This latch is mounted on the horizontal rock shaft 77. The latter is journaled in suitable bearing lugs on the base plate 5 and is provided at its left-hand end with an arm 78 which extends downwardly through an opening in the base and is connected by a link 79 to an arm 80 that depends from the left-hand portion of the starting bar or bail 23.

In the normal or zero position of the transmitter the latch 76 engages the lower end of the trip arm 70 and the roller 73 on the latter engages the cam lug 75 to thereby

hold the shaft 45 and clutch member 58 thereon forward with the spring 68 compressed and the cone 63 engaging the brake 64. When any transmitter key is actuated, the starting bar or bail 23 is depressed and latch 76 drawn down to release the trip arm. Spring 68 then serves to quickly engage the clutch members and the transmitter actuating shaft 44 is driven in the direction indicated by the arrows in Figs. 3 and 4. As soon as the cam lug 75 clears the roller 73 a light spring 81 (see Fig. 7) draws the trip arm forward so that it is re-engaged by the latch 76 as soon as the shifted key is restored to normal. The shifted key will usually be restored to normal before the shafts 44 and 45 complete a single revolution. Then, since the trip arm is locked by the latch 76, the engagement of the cam lug 75 with the roller 73 will shift the shaft 45 forwardly and move the clutch member 58 thereon out of engagement with the driving member 57 and into engagement with the brake 64, so that the shafts 44 and 45 are arrested with the flat rear end of the cam lug 75 engaging the roller. This disengagement of the clutch is aided by the momentum of the moving parts and the preferred clutch and brake construction set forth acts efficiently to effect the quick starting from and stopping in zero position of the transmitter actuating shaft.

As shaft 44 rotates the cams 43 thereon move in succession over the rear ends of the corresponding switch shifters 40. The lugs 42 on the latter are, however, normally out of the path of movement of the cams 43 but, when a key is depressed, one or more of the selecting or controlling fingers 30 are moved forward and lift the rear ends of the corresponding switch shifters so that the lugs 42 thereon are engaged by the respective cams 43 as shaft 44 rotates, and this operation of the cam lugs will depress the rear ends of the switch shifters, the forward ends of the selecting or controlling fingers, and the common transverse bar 31 of the bail 32, to thereby open the transmitter switch contacts 37 and 38. Shaft 44 is also provided with an additional starting cam 82, which is disposed in advance of the cams 43 and is arranged to engage a lug 83 fixed to the bar 31. Unlike the lugs 42 of the switch shifters, lug 83 lies in the path of its operating cam and is engaged thereby during the initial portion of each revolution of shaft 44 to shift the transmitter contact 37.

The cams 43 and 82 are preferably formed upon separate disks held in place on the shaft by spacing washers 84 and a nut 85, to thereby form in effect a single cylindrical cam member or support the surface of which is divided into seven equal spaces or units. The cams 82 and 43 extend in succession

through six of these spaces, leaving one space unoccupied. The vacant space or gap of the cam supporting member, in the zero position of the transmitter shaft, lies above the lugs 42 of the switch shifters and the lug 83 on the bar 31. At each revolution of the shaft cam 82, as stated, engages the lug 83 to impart an initial or starting impulse to the line. Cams 43 then pass in succession over the rear ends of the switch shifters 40 and, during the interval that each cam passes over the lug 42 of the corresponding switch shifter, the transmitter switch contacts are either opened or closed in accordance as to whether or not the rear end of the switch shifter has been raised by the corresponding controlling finger 30. A starting pulse followed by a permutation of two different line conditions, and representing a character signal, is thus imparted to the line at each revolution of the transmitter shaft.

As shown, the cams 43 and 82 are provided with concentric outer edges and beveled end portions, and the extreme beveled ends of adjacent cams terminate in alignment, as most clearly shown in Fig. 4. The lugs 83 and 42, which co-operate with the cams, are correspondingly beveled and the arrangement is such that the starting pulse or interval and the five intervals or pulses of the selective signal code are of uniform length. Also, with this arrangement, the pulses or line conditions follow each other with no gaps or spacing intervals between them.

Means are provided for locking the shifted keys and holding the other keys against operation. For this purpose a lock bar 86 extends transversely below the key levers 16 and is provided with a beveled rear edge arranged to co-operate with beveled lugs 87 formed upon the fingers 21 of the key levers. The lock bar is attached to the lower ends of two rock arms 88 which extend upwardly through openings in the base 1, one being pivoted to a lug on the bracket 35 and the other to a bracket 89 on the base. The right-hand arm 88 is provided with an upwardly and rearwardly inclined extension and carries a roller 90 arranged to engage the periphery of the disk 53. A spring 91, connected to the right-hand arm 88, holds the roller in engagement with the disk 53 and the latter forms a cam for operating the lock bar. This disk is circular through the greater portion of its periphery, but is provided with a recess which is engaged by the roller 90 in the zero position of the transmitter, so that the lock bar 86 is held out of the path of movement of the lugs 87. As soon as the key is depressed, however, the cam 53 shifts the lock bar rearwardly and co-operates with the lugs 87 to hold the shifted key lever in actuated position and the other key levers against movement. Preferably the cam 53 and lock bar 86 are arranged to co-operate with the beveled lug 87 of the selected key to complete its shift. Slightly in advance of the completion of each revolution of the transmitter actuating shaft 44 the roller 90 drops into the recess of the cam 53 and the shifted key and parts controlled thereby are restored to normal in readiness for the transmission of the succeeding signal. Preferably, in order to permit rapid operation of the transmitter keyboard, the recess of cam 53 is of such length that the keys are unlocked and restored to normal during the transmission of the third or fourth interval or pulse of each signal, but this necessitates the use of some means for storing the last or the last two impulse selections. In the form shown, the cam recess is of such length that the keys and signal selecting bails or bars are released and restored to normal during the transmission of the fourth pulse of each signal, and means, most clearly shown in Fig. 5, are provided in connection with the fifth impulse controlling finger for permitting the operation of a key during the transmission of the fifth pulse.

The arm 29 of the fifth bail is cut off and is provided with an upwardly extending spring arm 92 to the upper end of which the corresponding controlling finger 30' is pivoted. The latter extends rearwardly of its pivot and a light spring 93 extends between its rear end and the arm 29. The controlling finger 30' is provided near its forward end and on its lower edge with a short lug 94, which normally lies in rear of the bar 31. The fifth impulse cam 43, as shown, is provided with an extension 95 of the same length as the other cams but of less height and arranged in line with the fourth impulse cam. When a key which selects the fifth bar or bail 23 is depressed, the projection 94 on the corresponding controlling finger 30' will strike against the bar 31, so that the controller cannot be shifted to lift the corresponding switch shifter and the spring arm 92 will be flexed as shown in full lines in Fig. 5. The depression of the key will also, of course, close the transmitter clutch and start the rotation of the shaft 44 and cam 53 thereon, and the latter will shift the locking bar and hold the selected key down, as also indicated in Fig. 5. Then, when the bar 31 is depressed by the engagement of the starting cam 82 with the lug 83, the spring 93 can then slightly lift the forward end of the controller 30' so that the flexed spring arm 92 will shift it forward to the position indicated in dotted lines in Fig. 5, and thereby raise the fifth impulse switch shifter 40. In this position the lug 94 will be in front of the bar 31 and, at the proper time, the fifth impulse cam 43 will engage

and actuate the fifth impulse switch shifter. The locking bar releases the shifted key as soon as the fourth impulse has been transmitted, but the fifth impulse controller 30' is 5 prevented from moving back to normal position—in case the bar 31 is depressed by the fourth impulse cam—by the extension 95 of the fifth impulse cam. This extension holds the controller 30' sufficiently downward to 10 prevent its projection 94 from clearing the bar 31. As spring 93 is much lighter than the spring 39, of the rocking bail 32, its action can not open the contact. If the fifth bar or bail 23 has been selected for a letter, the 15 controlling finger 30' remains in its shifted left-hand position at the completion of the transmission of the character signal, and the spring arm 92 will be flexed in the opposite direction from that indicated in Fig. 5. If 20 the fifth bar or bail is selected for the succeeding character, the controlling finger 30' remains in shifted position; but, if it is not selected, it will slip back over the bar 31 when the starting cam 82 moves the bar 25 downwardly. If desired, similar storing means could be associated with the fourth impulse selecting devices. This arrangement for storing the fifth pulse selections of 30 the code signals permits of the rapid operation of the transmitter in sending a message, and, indeed, without arresting the transmitter shaft, since the keys can be operated so rapidly that before the transmitter and clutch shafts 44 and 45 have completed 35 a revolution the latch 76 will have been shifted to released position and the trip arm 70 will not act to open the clutch. Nevertheless, as the cams 82 and 43 and the blank portion of the cam member on the shaft 44 40 pass in succession over the lug 83 and the lugs 42 of the switch shifters, the code signals preceded by a starting pulse or interval will be properly imparted to the line and will be separated by spacing intervals during 45 which the line is restored to normal condition. Of course, during pauses in the operation of the finger keys, or at the end of the transmission of a message, the latch 76 and trip arm 70 will act as described to arrest 50 the transmitter in zero position, ready for further operation.

The parts of the receiver selecting mechanism and printer are mounted on the rear bracket 46 and a front bracket 96 secured to 55 the base plate 5. The upper portions of these brackets are connected by horizontal brace bars 97. The receiver has a main shaft 98, which is journaled at its forward end in a bearing 99 on the upper portion of the 60 bracket 96, and its rear end extends through an opening in the upper portion of bracket 46 and is journaled in a bearing 100 carried by a U-shaped support 101 fixed to the rear face of the bracket. Shaft 98 is actuated 65 from the continuously operating motor-

driven shaft 49 through a clutch on a shaft 102 parallel to shaft 98 and journaled in bearings 103 and 104 mounted, respectively, in the rear bracket and in a small bracket 105 on the base plate.

The receiver clutch is similar in construction to the transmitter clutch and comprises a driven member 106 pinned to shaft 102 and having external and internal cone surfaces which co-operate, respectively, with a 70 cup-shaped driving member 107 and an annular brake 108. The driven member 106 is formed of metal and is provided with an integral gear 109 that meshes with a gear 110 75 that is of the same size and is fixed to a collar 80 111 on the main shaft 98. The driving clutch member 107 is provided with a wooden liner 112 for engagement with the external surface of the driven member 106. The brake 108 is provided with a wooden cone 85 113 adapted to engage the internal surface 90 of the driven member. A clutch trip lever 114 is pivoted in a lower yoke 115 and is guided in the upper yoke 116, which yokes are mounted on the bracket 46 and project rearward therefrom. The trip is held in normal position by a toggle latch controlled by the armature of the magnet 3. In other respects the arrangement of the receiver clutch and brake and the parts connected thereto are 95 similar to the corresponding parts of the transmitter clutch and brake and are correspondingly numbered. It should be noted, however, that the worm gearing between the driving shaft 49 and the two clutch 100 shafts is such that the receiver shaft 98 is driven at a speed slightly greater than that at which the transmitter shaft 44 is driven. In the form shown, the worm wheel 105 on the clutch shaft 45 of the transmitter has thirteen teeth and that upon the receiver clutch shaft 102 has twelve teeth. Normally the clutch shaft 102 is held in its forward position by the engagement of a flat end of the eccentric cam lug 75 thereon with the roller 73 on the trip 114 and with the driven clutch member in engagement with the brake 108 and with the actuating spring 69 compressed.

The receiver magnet 3 has two spools in 115 the form shown, and depends from a horizontal support 117 projecting rearwardly from bracket 46. It is provided with a light armature 118 connected by pivot screws 119 to ears formed upon the outer end of the support 117. A light spring 120 extends between the armature and an adjusting screw 121 and tends to hold the armature in engagement with the lower end of an adjustable stop screw 122. Screws 121 and 122 120 are threaded through two rearwardly projecting lugs 123 on the upper portion of the support or yoke 101. The magnet 3 is preferably arranged in a closed circuit and normally holds its armature 118 down against 125 130

the tension of the spring 120, but, if desired, this arrangement could be reversed and the magnet arranged in a normally open circuit. Preferably the magnet is connected in circuit with the transmitter contacts 37 and 38 of the apparatus, so that it responds to the operation thereof as well as to the operation of transmitter contacts located at the distant station or stations.

10 The outer pivot pin 119 of the armature also forms the pivot for one member, 124, of the toggle latch which controls the trip lever 114. The other member 125 of the latch is in the form of a double link and is connected by a pivot 126 to the upper end of the trip lever. The two toggle members are connected by a rule joint adapted to be fixed in one direction only (upwardly in the form shown), and comprising a pivot 127 and a 20 stop 128 formed on the member 125 and adapted to be engaged by the extended forward end of the toggle member 124. A light spring 129, connected to the outer end of the pivot pin 127 and to the stud of the 25 roller on the trip lever, normally holds the forward end of toggle member 124 in engagement with the stop 128. In this position the pivots of the toggle members lie in a line extending at right angles to the trip lever, 30 so that pressure exerted on the roller 73 by the cam lug 75 cannot trip the latch. The trip lever is thus locked in normal position to hold the receiver clutch open but a slight upward pressure on the members of the 35 toggle latch will throw their pivots out of alignment so that they can be flexed as shown in Fig. 15 and permit the rearward shift of clutch shaft 102 by its spring 69 to thereby move the driven clutch member 106 out 40 of engagement with the brake 108 and into engagement with the driving member 107. This release of the toggle latch is effected by a lug 130 that extends laterally from the armature 118 beneath the toggle member 124. 45 To permit the easy flexing of the toggle, the forward end of member 124 and the face of the stop 128 engaged thereby are beveled as shown.

The toggle latch is thus tripped when 50 magnet 3 is deenergized by the starting pulse or interval of each signal and the receiver clutch is closed to thereby effect the rotation of the main shaft 98. When the magnet is energized to pull down its armature, 55 spring 129 will restore the toggle members to their aligned, locking position. This will occur during the spacing intervals between signals, so that at the end of the revolution of the receiver shafts 98 and 102 the eccentric cam lug 75 on the latter will ride up on the roller 73 of the trip 114 to open the receiver clutch, shift the driven member thereof into engagement with the brake, and arrest the receiver shafts 98 and 102 and parts 60 operated thereby. As in the case of the

transmitter clutch, this opening movement is aided by the momentum of the moving parts. The brakes of the two clutches can be so adjusted that the extent of movement required of the clutch shafts is slight, and the clutch and brake members act to start and stop the actuated parts quickly and with certainty. To aid in effecting quick starting of the receiver clutch, the co-operating cone surfaces of the driven member and brake 75 are inclined at a somewhat sharper angle than the engaging faces of the driving and driven clutch members. The end thrust on worm shaft 49, incident to the starting and stopping of the transmitter and receiver 80 shafts, is taken up by a washer 49' (see Fig. 13) fixed to the outer end of shaft 49 and co-operating with the adjacent bearing. Preferably, anti-friction balls are interposed between the bearing and the washer. 85

During each revolution of main shaft 98, magnet 3 responds to the five varied pulses or selecting intervals of the transmitted signal and co-operates with means rotated by the shaft to position a set of five selectors. 90 The latter, in the form shown, comprise pins or plungers 131 slidably mounted in the ends of a horizontal yoke or support 132 and arranged in an arc concentric with shaft 98. Support 132 is fixed to the upper end of the rear bracket, extends forwardly therefrom, and has two downwardly projecting arms 133 that engage the brace rods 97. The selector pins or plungers 131 are normally held in rearward or retracted position and are shifted forwardly by a set of levers 134 which, in turn, are operated by a series of pins 135. The latter are mounted in bearings 136 on bracket 46 and are arranged in a circle concentric with shaft 98. The levers 105 134 are centrally pivoted in the forked rear ends of studs 137 fixed to the bracket 46. The levers are of different lengths and are so shaped that, as most clearly shown in Fig. 8, the upper and lower ends thereof, respectively, engage the rear ends of the selecting pins and heads on the rear ends of the actuating pins 135. Separate leaf springs 138, fixed to the support 132, extend forwardly over the selecting plungers and are provided with depending V-shaped forward ends that engage small, circular, bevel-edged lugs fixed to the plungers. When the lugs are in the rear of the V-ends of the springs, the latter hold the plungers, the levers 134 and pins 135 in normal retracted position with the heads of the pins engaging the bearings 136. 110

The forward ends of the pins 135 extend through notches 141 formed in a cam ring 142 that is secured to the front face of the bracket about the opening therein through which shaft 98 extends. The cam ring is concentric with the shaft and the latter carries a spring-actuated shuttle 143 having a 115 120 125 130 135 140 145 150 155 160 165 170 175 180 185 190 195 200 205 210 215 220 225 230 roller 144 thereon arranged to engage the cam. The shuttle is cylindrical and is mounted on a sleeve 145 fixed to the shaft by set screws 146 extending through a flange 147 thereon. The roller 144 is journaled on an arm of the shuttle and, as stated, engages the face of the cam ring. To avoid sliding friction, the engaging faces of the roller and cam are conical. A horizontal pin 148, fixed 10 to the shuttle arm, extends through an opening in the flange 147 and compels the rotation of the shuttle with the shaft, but permits its axial movement on the sleeve. Preferably, anti-friction rollers are interposed between the sleeve and shuttle. A 15 spring 149 on pin 148 presses the shuttle rearwardly and holds the roller in engagement with the cam, and also serves to force the roller into the cam notches 141 against the pins 135 to thereby shift the levers 134 and the selecting pins or plungers 131. This 20 spring also takes up any end play of the shaft 98 and holds it in position, with a shoulder 150 thereon engaging the shaft 25 bearing 99.

The shuttle has a flange 151 on its near end which co-operates with a finger 152 projecting forwardly from the armature 118 and secured thereto by screws 152'. These screws 30 extend through short slots in the finger 152, so that the position of the latter can be adjusted. As the circuit of magnet 3 is opened and closed, the shift of its armature moves the rear end of the finger 152 into and out 35 of the path of the axial movement of the shuttle (see Figs. 12 and 15) and, as shaft 98 and the shuttle rotate, the roller 144 drops successively into the notches of the cam ring 142, but if the magnet is deenergized and its armature raised at the time 40 the roller passes through one of the notches the rearward shift of the shuttle, effected by the spring 149, will be arrested by the engagement of the finger with the shuttle flange 151 and the roller will not drop into 45 the notch far enough to actuate the corresponding pin 135. If, however, the magnet is energized at this time, its armature will be held down and the rearward shift of the 50 shuttle and roller completed to thereby engage and shift the pin and move the corresponding selecting plunger 131 forward. When any selecting plunger is thus shifted, the beveled-edge lug 140 thereon passes 55 beyond the V-end 139 of its spring and is thereby held in shifted position.

The shaft 98 and the selector-actuating shuttle thereon rotate at such a rate and the notches 141 of the cam ring are so uniformly and angularly spaced that the roller 144 passes through the notches in synchronism with the five selecting impulses or units of the transmitted signals, and so shifts the selecting plungers forwardly or leaves them 60 in normal retracted position, as the circuit

of magnet 3 is either closed or opened by the corresponding selecting impulses of each signal.

The shuttle is so positioned on the shaft that the roller thereon registers with or 70 passes through notches 141 of the cam ring 142 during the mid-portions of the selecting intervals or units of the transmitted signals, as indicated in Fig. 16, so that the magnet changes the position of its armature 75 while the shuttle roller is on the high portions of the cam. And since the high cam portions then hold the rear end of the shuttle spaced slightly in front of the path of movement of the forward end of the finger 80 152, the magnet can shift its armature freely. Moreover, since the high cam portions are of considerable length, the synchronism between the receiver of one apparatus and the signals transmitted thereto from a distant station need not be exact and can be 85 distorted considerably without interfering with the proper operation of the receiver. In other words, the positions in which the rotary receiving member is operative upon 90 the selectors, as determined by the spaced notches of the cam 142, extend through relatively short arcs as compared with the corresponding operating positions of the rotary transmitter member, as determined by 95 the cam sections 43 that impart the selecting intervals of the signals to the line. To insure with the proper operation of the receiver member during the spacing interval at the end of each signal, it is driven, as stated, 100 slightly faster than the rotary transmitter member and, in order that the rotary receiver actuating member shall pass through its operating positions during the midportions of the signal intervals, the notches of 105 the receiver cam are not only relatively shorter than the corresponding operating portions of the transmitter cam, but are angularly spaced farther apart than the centers of the transmitter cam sections. In 110 other words, the selecting units of the receiver cam are relatively longer than those of the transmitter cam to compensate for the difference in speed, and the portions of the receiver cam that correspond to the starting 115 and spacing intervals are relatively shorter. The relative shortening of the starting and stopping portions of the receiver cam is indicated in Fig. 16, but otherwise no attempt is made to indicate this relative difference in speed. 120

The position of the shuttle and of the roller 144 thereon can be adjusted in circumferential direction on shaft 98 by means of the set screws 146, which, as shown in 125 Fig. 12, engage an annular groove in the shaft. The shuttle is thus set to take care of the lag in the starting operation of the receiver clutch, and which, as described, is effected by the starting impulse of each sig- 130

nal. The shuttle will be so set that its roller will pass through the first notch of the cam at the mid-portion of the first selecting impulse or interval. The relation of the portions of this cam to the intervals or units of the signals is indicated in Fig. 16. The difference in length between the starting interval of the signal and the starting portion of the cam represents the lag in the starting operation of the receiver clutch. As noted the high portion of the cam between the fifth and first notches thereof, and which corresponds to the starting pulses and separating intervals between the signals, is relatively shorter than the corresponding sections of the transmitter so that the entire receiver cam is preferably about $6\frac{1}{2}$ units in length. The starting and stopping positions of the pin-actuating roller are indicated in full and dotted lines in Fig. 16, but, of course, these positions are coincident; as already noted, the zero position of the roller can be adjusted to take care of the lag in the operation of the starting clutch.

When two or more machines are connected or placed in communication, the motors are set to run at substantially the same speed, but, as noted, the receivers are so geared to the motor shafts that they run slightly faster than the transmitters and are invariably arrested during the spacing intervals between the signals and again started in exact phase with the transmitted impulses by the initial starting pulse of the succeeding signal. In other words, any variation in phase between a receiver and the signals transmitted thereto from a distant station is corrected at the intervals between the signals, so that there can be considerable variation in the speeds of the motors at different connected stations. Hence, although the timing of the transmitters and receivers during each signal period is determined by the rate of speed of the local motors, the means for adjusting the speed of the motors at different connected stations does not require frequent attention. It should also be noted that the transmitter and receiver of each apparatus are independently driven by the motor. For this reason, and since the operation of the transmitter switch is initiated independently of the starting impulses, and imparts the starting intervals to the line after it leaves or passes through its normal or zero position, the relation between the starting and selecting impulses of the transmitted signals is in no way affected by the lag in the operation of the starting magnet, clutch, or other electrically controlled starting means. On this account, the receiver need not be frequently adjusted to take care of variations in the lag of starting means of transmitters located at different distant stations, and to which the receiver is connected. Again, since the starting or correct-

ing impulses accompany all transmitted signals, no adjustment of the receiver is required to take care of line lag. As already noted, the receiver shuttle chiefly requires adjustment to take care of the lag in the operation of its own local starting means, and this adjustment can be made when the machine is set up and, for the most part, does not have to be changed unless something affects the time of operation of its starting clutch.

While various recording means could be used, means similar to that shown in the United States patent to Baudot, No. 388,244, dated August 21, 1888, is preferably employed. However, instead of employing continuously rotating combiner disks and type-wheel, as in the Baudot printer, these parts are connected to, and are preferably mounted on, the intermittently rotating shaft 98. The combiner disks 153 and 154, having a flange 155 clamped between them, are mounted on a collar 156 on shaft 98 in rear of the front bracket. One of the disks and the flange are preferably annular and are fixed to the rim portion of the other disk, the hub of which is secured to the collar 156, the latter being fastened to the shaft by set screws 157. The peripheries of the combiner disks are provided with raised portions and notches or recesses, and are engaged by a set of five selecting fingers or feelers 158. The latter have upper ends of inverted U-shape and are fixed to a set of short, horizontal, pivot pins 159 that are rotatably and slidably mounted in a support which is fixed to the upper portion of the front bracket and projects rearwardly therefrom. This support comprises a plate 160 and a U-shaped member 161.

The upper portions of the selecting fingers have integral contact heads 162 and the head of the left-hand finger is engaged by a head 163 formed upon a rearwardly projecting arm 164 of a lever 165. This lever is arranged in front of the plate 160 and its rearwardly projecting arm 164 is provided with a depending portion 166, having lugs that are fixed to a pivot pin 167, which is like the pivot pins 159 and similarly mounted in the plates 160 and 161. A spring 168, connected to an adjusting screw 169 and to the lever 165, forces the head 163 of the lever to the right and holds the contact heads 162 in engagement with the selecting fingers 158 bearing on the peripheries of the combiner disks 153 and 154.

The contact heads and the pivot pins of the lever 165 of the selecting fingers are arranged in arcs concentric with the shaft 98, and the pivot pins 159 of the selecting fingers are arranged, respectively, in alignment with the selecting plungers 131. In their retracted positions the selecting fingers 158 rest upon the combiner disk 153, but they are

adapted to be shifted through a gap in the flange 155 by the plungers 131 and into position over the combiner disk 154, as shown in Fig. 12. A restoring cam 170 on the combiner disk 154 extends through the gap of flange 155 and, near the end of the revolution of shaft 98, engages and restores any of the selecting fingers 158 that have been shifted.

The combiner disk 153 has a number of rearwardly projecting studs 171 which carry a thin, sheet metal, stop flange 172. The latter is annular in form and is arranged to engage the lugs 140 on the selecting plungers 131 and arrest the forward movement thereof when the latter are advanced by the selector-actuating shuttle, as previously described. The V-ends 139 of the springs 138, which engage the lugs 140 and hold the selecting plungers 131 in retracted position, also hold them, when advanced with the lugs, against the rear face of the stop flange 172. The latter is provided with a gap within which are arranged two oppositely-inclined cams 173 and 174, formed upon a U-shaped piece 175 that is mounted on a block 176 on the rear face of the combiner disk 153. The lugs 140 of the selecting plungers 131 are normally out of the path of movement of these cams, but when the plungers are advanced, the cam 173, near the end portions of the revolution of shaft 98, will engage the lugs and further shift the plungers forward to thereby move the corresponding selecting fingers 158 from engagement with the combiner disk 153 through the gap in flange 155, and into engagement with disk 154. Immediately after this operation cam 174 engages the lugs 140 of the shifted plungers and restores them completely to their retracted position.

The restoring cam 170 for the selecting fingers 158 is arranged slightly in advance of the cams 173 and 174, as shown in Fig. 12, and these three cams act successively near the end portions of the revolution of shaft 98 to restore the fingers 158 that have been shifted at the previous operation, actuate the plungers 131 to again set the fingers, thus transferring the received signal from one set of selectors to the other, and finally to restore the plungers in readiness to be positioned during the succeeding operation and in accordance with the varied selecting impulses of the next signal. The parts of the receiver are shown approaching their normal zero position in Figs. 10 and 12, and in this position in the other figures.

While as stated, the blank portions of the receiver cam which correspond to the starting and spacing intervals of the signals are relatively shorter than the corresponding portions of the rotary transmitter member, nevertheless, as is clear from an inspection of

Fig. 13, the angular space between the last 65 and first selector operating positions of the actuating shaft 98 as determined by the angular spacing of the pins 135 is considerably greater than the other uniform spaces 70 between the pins, so that ample opportunity is afforded for the adjustment of the stopped position of the selector actuating shuttle relative to its operating positions, and for the operation of the cams 170, 173 and 174 75 by the movement of the shaft, before the first selector setting of the succeeding operation.

A type-wheel 177 and a toothed wheel 178 for operating a printing arm are mounted on the forward end of the shaft 98 and rotate 80 therewith. Wheel 178 is arranged to engage a tooth 179 on the inner end of a printing arm 180. The latter is pivoted on a stud 181 projecting forwardly from bracket 96, and a spring 182, connected at its outer end to an adjusting screw 183, tends to throw its inner end upwardly. Normally, however, the arm is held down by a catch 184 pivoted on the bracket 96 and engaging a lug 185 on the inner end of the arm. A spring 186 connected to the catch holds it in normal position with its lower end in engagement with an adjustable stop screw 187, and with a laterally projecting arm 188 on the catch 90 engaging the left-hand end of a trip 189. The latter is centrally pivoted on the bracket 96 and its right-hand end is connected to the end of the lever 165 by a link 190 that is preferably formed of two adjustably connected sections. 100

The paper tape on which the characters are printed passes over a fixed guide pin 191, thence over a guide pin 192 on the arm 180, around an impression roller on the end of 105 the arm, and thence over a feed wheel 194 that is journaled on stud 181. A spring-held support 195, pivoted on a stud 195', carries a pressure roller 196 that holds the tape in engagement with the feed roller. 110

As stated, the selecting fingers 158 are set in accordance with the signal that is received during each revolution of the shaft 98. At the next revolution of the shaft the combiner disks rotate below the ends of the 115 selecting fingers. As in the Baudot printer, the pressure of the head 163 of the spring-actuated lever 165 against the contact heads 162 of the selecting fingers 158 prevents any of the fingers from dropping into recesses of the combiner disks until the latter have moved to such a position that all five fingers can drop into recesses thereof. When this occurs, the lever 165 is lowered and the continued movement of the disks forces the 120 selecting fingers upwardly and quickly lifts the lever 165. The combiner disks are so notched or recessed that this movement of the lever occurs when the character on the 125

type-wheel, that corresponds to the particular setting of the selecting fingers, is in position opposite the impression roller 193.

The oscillation of the lever 165 thus effected first lifts and then quickly throws down the left-hand end of the trip 189, so that it strikes and releases the catch 184. The spring 182 then moves the arm 180 and engages its tooth 189 with the wheel 178 and the latter swings the arm on its pivot, presses the paper on the impression roller against the proper character on the typewheel, which at this instant is in printing position, and moves the arm to the position shown in dotted lines in Fig. 10. The arm is arrested in this position, with its tooth 179 disengaged from wheel 178 and with the impression roller out of contact with the type-wheel, by the engagement of a lug 197 on the arm with the lower end of a pivoted restoring lever 198, which at this time engages stud 195. At the end of the revolution of shaft 98 a roller 199, on the rear face of wheel 178, engages the upper end 25 of the restoring lever and the latter shifts the printing arm back through blank spaces in the wheels 177 and 178 to its normal position in engagement with the catch 184.

As in the Baudot printer, the shift of the arm 180 effects the letter space feed of the paper tape through the medium of spring-pressed holding and feeding pawls 200 and 200', pivoted, respectively, on the arm and on the bracket 96 and engaging a ratchet 201 fixed to the feed roller 194. A suitable inking roller 202 for the type-wheel is mounted on a pivoted spring-held arm 203.

A blank portion of the type-wheel is adapted to be brought to printing position 40 in response to a spacing signal. Since the selectors are set during one revolution of the receiver and the corresponding character printed at the next revolution, and since the receiver is arrested after each revolution, the spacing signal must be transmitted to effect the printing of the last character of the message.

Preferably, the type-wheel has two sets of type and is shiftable relatively to the toothed wheel 178 which controls the movement of the printing arm 180. For this purpose the type-wheel and an arm 204 are fixed to the ends of a common hub 205, which is loosely mounted on the forward end of the shaft and is held in place thereon by a washer 206. A spring-held catch 207, pivoted on wheel 178, has two notches for engaging the beveled end of arm 204 to thereby hold it and the type-wheel in either one of two positions relatively to the toothed wheel. The opposite end of arm 204 engages a shifter 208 centrally pivoted on wheel 178 and having two projections 209 which, as the shifter is operated, alternately overlap 55 two of the spaces between the teeth of the

wheel, one or the other of which is adapted to be engaged by the end of the printing arm 180. At points corresponding to these two spaces of the toothed wheel, the type-wheel is blank, so that, by sending suitable shifter signals, the printer arm can be actuated to engage the projections 209 of the shifter and thereby adjust the position of the arm 204 and the type-wheel relatively to the toothed wheel 178 and bring either set of type into operation.

Modifications of the selector mechanism are shown in Figs. 17 to 20, inclusive. In these forms the receiver magnets 210 are horizontally disposed and the armatures 211 thereof are mounted on vertical spring-held levers 212. The armature lever, in the form shown in Figs. 17 and 18, has a fork 213 at its upper end and pins 214 thereon engage an annular groove of a shuttle 215 that is keyed to and is axially shifttable on the main shaft 98. An arm 216 on the shuttle is provided at its end with a beveled cam 217 that is rotated by the shaft 98 past the forward ends of the selector shifting pins 135 and is moved into and out of operative relation with the pins as the circuit of the magnet is opened and closed.

In the form shown in Figs. 19 and 20, the armature lever has an annular part or ring 218 which surrounds and is concentric with the shaft 98 and is provided with a set of five internal cam lugs 219. A sleeve 220, fixed to the shaft, has a lug 221 thereon, to which an actuating arm 222 is centrally pivoted. The arm is provided with inclined cam ends which co-operate, respectively, with the inclined faces of the cam lugs 219 and with the forward ends of the pins 135. A spring 213 tends to hold the rear end of the arm 222 against a stop lug 224 on the sleeve. As the actuating arm is rotated by the shaft, the armature lever is shifted by the magnet to move the cam ring 218 thereon into and out of the path of movement of the forward end of the actuating arm 222 and its rear end is shifted by the cam lugs 219 into and out of operative relation with the selected shifting pins 135. The cam lugs are, of course, spaced in accordance with the spacing of the pins 135, each lug being arranged slightly in advance of the corresponding pin.

In both of the modified forms, as in the form previously described, the pins 135 and the corresponding selecting plungers 131 are shifted or remain in retracted positions as the magnet circuit is opened and closed in response to the varied selecting impulses of each signal. In each of the forms, the rotary movement of the selector actuating member, while initiated by the selecting magnet in response to the starting condition of each signal, is effected under local control by the motor-driven receiver shaft, so that

this rotary movement of the actuator through its successive operating positions is thereby locally timed. Also, in the main form of the selector mechanism and in the 5 modification shown in Figs. 19 and 20, the transverse selecting movement of the actuator is effected and locally timed by the rotary movement of the main shaft, and the selecting magnet solely controls such reciprocating movement. Also, in these forms, 10 the arrangement is such that the selector setting operations are effected without opposing the operation of the selecting magnet and without applying pressure upon the armature lever in a manner tending to disturb its setting as determined by the magnet. The improved receiver mechanism is particularly applicable for use in connection 15 with the start and stop clutch mechanism, but certain features thereof could be employed in a receiver in which other means is used for maintaining its operations in synchronism with the received signals.

The different arrangements of the circuit 20 which can be employed are shown in Figs. 21, 22 and 23. In Fig. 21, three combined keyboard transmitters and printing receivers at different stations are connected in series in a common line, the receiver magnets 25 3 being interposed directly in the line circuit. In Fig. 2, line relays 225 control local circuits for the receiver magnets. Obviously, these local circuits could be normally closed as shown, or normally open. At one 30 station in Fig. 22, a modified transmitter, adapted for use with a perforated tape, is provided with a set of five impulse selecting switches 226 and a collecting transmitter switch. The latter comprises a continuous 35 ring contact 227 and seven segments of equal length adapted to be connected by a rotating brush 228. This brush takes the place of the rotary actuating cam member in the transmitter already described, and, like this 40 cam member, is driven from the station motor through the medium of the transmitter start and stop clutch mechanism. After each 45 signal and when its operation is arrested, the brush is in engagement with the segment I. This segment is connected directly 50 to the line battery and the segments 1, 2, 3, 4 and 5 are connected to the battery by the normally closed selecting switches 226, that are adapted to be variably controlled by a 55 perforated tape or, if desired, by a keyboard such as previously shown and described. No connection is made to the segment S which imparts the starting impulses or intervals to the line. The operation of this 60 transmitter is substantially similar to that of the transmitter previously described, except that when the tape is employed to control the set of impulse selecting members or switches 226 a magnet 229 for shifting the 65 switches, intermittently advancing the tape and tripping the clutch, is provided and its circuit is energized by a suitable switch operated by the transmitter shaft 44, upon which the rotating transmitter brush 228 is mounted. In the arrangement shown, contacts 230 interposed in the circuit of this magnet are engaged by a notched cam 231 mounted on the transmitter shaft, the cam being so disposed that the magnet circuit is closed when the transmitter brush is in engagement with the segment I. A manually operative switch 232 is interposed in the circuit of the magnet to start and stop the operation of the transmitter.

Fig. 23 shows one of the terminal stations 70 of a duplex line circuit. The contacts of a keyboard transmitter, the magnet of a printer, and a transmitting relay 233 are arranged in series in a local circuit. The printer in this circuit acts solely as a home recorder and the printer for recording received messages is arranged in another local circuit controlled by the tongue of a polarized line relay 234. As usual, the two coils of this relay are connected, respectively, to 75 main and artificial lines and both coils are connected to the coils of the transmitting relay 233, the latter having front and back contacts connected respectively to the unlike poles of a divided line battery. With this 80 arrangement negative current will be normally imposed upon the line and signals, consisting of a positive starting pulse and five selecting pulses of one or the other polarity, will be imposed upon the line by the 85 relay 233 under control of the transmitter switch contacts 37 and 35. The transmitter and receiving and home recording printers can all be operated from a common motor through separate start and stop clutches.

Other changes that have been indicated 90 may be made in the arrangement of the apparatus and circuits and in the details of construction, and parts of the invention can be employed without its adoption in 95 entirety.

We claim as our invention:—

1. In a receiving apparatus for selecting telegraphs, a set of selectors, a unitary rotatable actuator common to all of said selectors movable at an angle to its rotary path to effect the operation of selectors, a start and stop clutch for initiating and arresting the rotary movement of said actuator at the beginning and end respectively of each signal, and a single magnet responsive to the received signals for tripping said clutch and variably controlling the angular movement of said actuator.
2. In a receiving apparatus for selecting telegraphs, a set of selectors, a common selector actuator, a power drive for rotating said actuator into relation with said selectors in succession, said actuator being movable at an angle to the rotary path into position to

shift said selectors, means for synchronizing the rotation of said actuator with the received signals, and a magnet responsive to the signals for variably controlling the angular movement of said actuator.

3. In a receiving apparatus for selecting telegraphs, a set of selectors, a common selector actuator, a power drive for rotating said actuator into relation with said selectors in succession, said actuator being movable at an angle to the rotary path into position to shift said selectors, means for synchronizing the rotation of said actuator with the received signals, and a magnet responsive to the signals for controlling said synchronizing means and for variably controlling the angular movement of said actuator.

4. In a receiving apparatus for selecting telegraphs, a circular series of selector shifters, a common actuator rotatable past said shifters in succession and axially movable to effect the operation of said shifters one at a time, a power drive for rotating said actuator under local control during each signal period, and a magnet responsive to the line conditions for controlling its axial movement.

5. In a receiving apparatus for selecting telegraphs, a circular series of selector shifters, a common actuator, a power driven start and stop clutch for rotating said actuator past said shifters in succession, said actuator being axially shiftable to effect the operation of said shifters one at a time, and a magnet responsive to the received signals for tripping said clutch and for variably controlling the axial movement of said actuator.

6. In a receiving apparatus for selecting telegraphs, a set of selectors, a rotatable selector actuator axially movable into and out of operative position, a cam having notches corresponding to said selectors and a magnet responsive to the received signals and cooperating with said cam to control the axial movement of said actuator.

7. In an electric selective apparatus, a circular series of selector shifters, a rotary, axially movable actuator, a power drive for rotating said actuator past said shifters in succession, a fixed notched cam ring, a spring for holding said actuator in engagement with said cam ring and for shifting the same axially into the notches thereof to effect the operation of said shifters, and a magnet for variably arresting the axial movement of said actuator.

8. In an electric selective apparatus, a set of selectors, a common rotary actuator therefor, a start and stop clutch comprising a driving member, a brake, and a driven member connected to said actuator and axially movable to alternately engage said driving member and said brake, a trip for controlling the axial shift of said driven member,

and means responsive to the received signals for controlling said trip and operation of said actuator.

9. In an electric selective apparatus, a set of selectors, a common rotary actuator therefor, a start and stop clutch comprising a driving member, a brake and an axially shiftable driven member connected to said actuator and spring-pressed into engagement with said driving member, a trip for shifting said driven member into engagement with said brake, a latch normally locking said trip in operative position, and electro-magnetic means responsive to the received signals for releasing said trip and variably controlling the operation of said actuator upon said selectors.

10. In an electric selective apparatus, a set of selectors, a common rotary actuator therefor, a start and stop clutch for said actuator, a trip for opening said clutch, a toggle latch normally locking said trip in operative position, and a magnet responsive to the received signals for flexing said toggle latch and for variably controlling the operation of said actuator upon said selectors.

11. In a telegraph receiver, a type wheel, a printing member, a set of selectors and rotary combiner discs controlling the operation of said printing member, a power driven start and stop clutch for rotating said type wheel and combiner discs and for arresting the same in a normal position at the end of each operation, and electro-magnetic means acting in response to the received signals for tripping said clutch and controlling the setting of said selectors.

12. In a telegraph receiver in which the signals consist of starting intervals and permutations of two different line conditions extending through a definite number of time intervals, a receiver comprising a type wheel having a normal position of rest, a co-operating printing member, a set of selectors controlling the operation of said printing member during the rotation of the type wheel, a power drive having a start and stop clutch for rotating said type wheel and arresting the same in normal position at the end of each signal, and electromagnetic means acting in response to the starting intervals of the received signals to trip said clutch and in response to the varied signal impulses to control the setting of said selectors.

13. In a telegraph receiver, a set of selectors, a rotary actuator therefor, a type wheel, a co-operating printing member, and means controlled by the setting of said selectors in different combinations for effecting the operation of said printing member, a power drive having a start and stop clutch for rotating said type wheel and said selector actuator and for arresting the same in normal position at the end of each signal, and an electro-magnet acting in response to the re-

ceived signals to trip said clutch and control the operation of said selector actuator.

14. In a telegraph receiver in which the signals each consists of a starting interval 5 and a code permutation of two different line conditions extending through a definite number of time intervals, a receiver comprising a type wheel, a co-operating printing member, a set of selectors controlling the operation .0 of said printing member, a rotary selector actuator, a power drive having a start and stop clutch for rotating said actuator and said type wheel and for arresting the same in normal position at the end of each signal, 15 an electro-magnet acting in response to the starting intervals of the received signals to trip said clutch and, to the code permutations to variably control the operation of said actuator.
- 20 15. In a telegraph receiver, a set of selectors, a rotary actuator therefor, a type wheel, a co-operating printing member, a second set of selectors controlled by the first set, combiner discs co-operating with said 25 second set of selectors to control the operation of said printing member, a common power driven shaft for said actuator, type wheel and combiner discs, and an electro-magnet controlling the operation of said actuator.

16. In a telegraph receiver, a set of selectors, a rotating actuator therefor, a type wheel, a co-operating printing member, a second set of selectors controlled by the first 35 set, combiner discs co-operating with said second set of selectors to control the operation of said printing member, a common power-driven start and stop clutch for rotating said actuator, type wheel and combiner discs and for arresting the same in a 40 normal position at the end of each signal, and electro-magnetic means responsive to the received signals for tripping said clutch and controlling the operation of said actuator.

- 45 17. In a telegraph receiver, a set of selectors, a rotating actuator therefor, a type wheel, a co-operating printing member, a second set of selectors controlled by the first set, combiner discs co-operating with said 50 second set of selectors to control the operation of said printing member, cams for advancing and restoring said selectors, a common power driven shaft whereon said actuator, type wheel, combiner discs and cams are mounted, and an electro-magnet for controlling the operation of said actuator.

18. In a telegraph receiver, a set of selectors, a rotating actuator therefor, a type wheel, a co-operating printing member, a 60 second set of selectors controlled by the first set, combiner discs co-operating with said second set of selectors to control the operation of said printing member, cams for advancing and restoring said selectors, a com-

mon power driven shaft whereon said actuator, type wheel, combiner discs and cams are mounted, a start and stop clutch for said shaft, and a magnet for tripping said clutch and controlling the operation of said actuator.

70 19. In a telegraph receiver, a set of selectors, a common rotary actuator, a power drive having a start and stop clutch for rotating said actuator and for locally timing its operation during each signal period, said actuator being shiftable at an angle to the rotary path to effect the operation of said selectors, electro-magnetic means responsive to the received signals for tripping said clutch and for controlling the angular movement of 80 said actuator.

20. A telegraph receiver, comprising a set of selectors, an actuator rotatable into relation with said selectors in succession and axially movable into and out of position to 85 shift said selectors, a printer, means mechanically co-operating with said selectors to effect the operation of said printer, and a magnet responsive to the received signals for controlling the axial movement of 90 said actuator.

95 21. A station equipment for selecting telegraphs comprising transmitter contacts, a set of receiver selectors, separate rotary actuators for mechanically operating said contacts and said selectors, power means for continuously rotating said transmitter and receiver actuators, during each signal period, correcting devices for said receiver actuator, electro-magnetic means responsive to 100 signal impulses for controlling said correcting devices and the operation of said receiver actuator, and means independent of said electro-magnetic means for controlling the operation of said transmitter actuator. 105

110 22. A station equipment for selecting telegraphs comprising transmitter contacts, a set of receiver selectors, separate rotary actuators for said contacts and said selectors, power means for rotating said receiver actuator and said transmitter actuator, a start and stop clutch for said receiver actuator, a single selecting-magnet responsive to the signals for tripping said clutch and controlling the operation of said receiver actuator, 115 and means independent of said magnet for controlling the operation of said transmitter actuator.

120 23. A station equipment for selecting telegraphs comprising transmitter contacts, a set of receiver selectors, separate rotary actuators for mechanically operating said contacts and said selectors, separate power driven start and stop clutches for said transmitter and receiver actuators and for locally timing the operations thereof during each signal period, electro-magnetic means responsive to signal impulses controlling the 125

operation of said receiver clutch and actuator and independent means for controlling said transmitter clutch and actuator.

24. A station equipment for selecting telegraphs comprising transmitter contacts, a set of receiver selectors, separate rotary actuators for mechanically actuating said contacts and said selectors, separate power driven start and stop clutches for continuously advancing and locally timing the operations of said rotary transmitter and receiver actuators during each signal period, electro-magnetic means responsive to signal impulses controlling the operation of said receiver clutch and actuator and independent means for controlling said transmitter clutch and actuator, said transmitter controlling means being arranged to permit the continuous operation of said transmitter actuator.

20 25. In a station equipment for printing telegraphs, a set of receiver selectors, a printer mechanically controlled thereby, a common actuator for said selectors having a normal position of rest, a transmitter member having a normal position of rest, power driven means for operating and locally timing the movement of said actuator and said member during each signal period, a single electro-magnet responsive to signal impulses for initiating and also for subsequently controlling the operation of said actuator and independent means for initiating and controlling the operation of said transmitter member.

35 26. In a telegraph receiver in which the signals are of uniform length and consist of starting intervals and permutations of two different line conditions extending through five units with spacing intervals between the 40 signals, of sets of five transmitting and receiving selectors at each of two connected stations, each station having transmitter and receiver shafts and an operating motor geared to rotate said receiver shafts slightly 45 faster than said transmitter shafts, separate start and stop clutches for said shafts, contacts for imparting the selected signals to the line operated by said transmitter shafts and controlled by the transmitting selectors, 50 receiving selector actuators and printers controlled thereby mechanically actuated by receiver shafts, a magnet at each station responsive to the line conditions for tripping said receiver clutches and for subsequently 55 controlling the operation of said selector actuators and independent means for controlling the transmitter clutches and selectors.

60 27. In an electric selective apparatus, a set of selectors, a rotary actuator for mechanically setting said selectors in different combinations, a power driven start and stop clutch for rotating said actuator into relation with said selectors successively, and 65 electro-magnetic means responsive to the

received signals for tripping said clutch and controlling the selector-setting operation of said actuator, the latter being adjustable circumferentially to compensate for the lag in the starting operation of said clutch.

70 28. In an electric selective apparatus, a set of selectors, a rotating actuator for mechanically setting said selectors in different combinations, a motor driven start and stop clutch for continuously rotating said actuator during each signal period to bring the same into relation with said selectors successively and for arresting the same at the end of each signal period, and an electro-magnet acting in response to the signals for 75 tripping said clutch and for variably controlling the selector-setting operation of said actuator.

80 29. In an electric selective system, the combination with a line circuit, of rotary transmitter and receiver shafts at different stations, motor driven start and stop clutches for rotating and locally timing the speed of said shafts during each signal period, start and stop clutches for said shafts, transmitter contacts and a receiving selector mechanism mechanically operated respectively by said shafts, electro-magnetic means responsive to received signals for tripping said receiver clutch and for controlling the operation of said selector mechanism, a keyboard for tripping said transmitter clutch and for selecting the signal impulses, a lock for said keyboard controlled by said transmitter shaft adapted to release the same before the completion of a signal, and means for storing one or more of the impulse selections for 90 each signal.

95 30. In a receiving apparatus for selecting telegraphs, a set of selectors, a common member for mechanically positioning said selectors in different combinations, said member being rotatably and axially shiftable into operative relation with said selectors in succession, a motor-driven clutch for continuously and uniformly rotating said member during each complete selecting operation and for arresting the same at the end of each such operation, and electro-magnetic means responsive to line impulses for tripping said clutch into operation and for selectively controlling the axial movement of said member.

100 31. In a printing telegraph, transmitter contacts and a set of receiver selectors, separate rotary members for mechanically operating said contacts and said selectors, motor-driven clutches for continuously advancing said members during each complete operation and operable to arrest the same only at the ends of each such operations, the operating positions of said receiver actuator being relatively shorter and angularly spaced relatively farther apart than those of said transmitter member and said clutches being 105 110 115 120 125 130

geared to rotate said receiver member at a correspondingly faster speed, an electromagnet responsive to line conditions for tripping said receiver clutch at the beginning of each 5 operation and for subsequently controlling the operation of the receiver actuator and means independent of the line conditions for tripping said transmitter clutch.

32. In a selecting apparatus for telegraph 10 receivers, the combination of a set of selecting devices, a unitary actuating member for mechanically positioning said selecting devices in different combinations, said actuator being rotatable past said selecting devices 15 in succession and axially shiftable into and out of position to operate said selectors, a motor-driven clutch for continuously rotating said member during each complete selecting operation and for arresting the same 20 at the end of each such operation and an electro-magnet responsive to signal impulses for tripping said clutch into operation at the beginning of each signal period and thereafter selectively controlling the axial movements 25 of said actuator.

33. In a selective apparatus for telegraph receivers, a series of selecting devices, a unitary actuating member rotatable into relation with said selecting devices successively 30 and axially movable into and out of position to operate said selecting devices one at a time, motor actuated driving means for continuously rotating said actuating member at each selecting operation, cam and spring means for axially shifting said actuator in 35 opposite directions and into and out of position to operate said selecting devices and a magnet responsive to the received impulses for variably controlling the operation of said 40 cam and spring means.

34. In a receiving apparatus for start-stop selecting telegraphs, an electro-magnet responsive to received code combinations of two different electrical conditions, a rotary 45 member, a set of selectors under the joint mechanical control of said rotary member and the armature of said magnet and selectively conditioned thereby, one at a time, in different combinations, and a motor-driven, 50 start-stop clutch means mechanically controlled by the armature of said magnet for continuously advancing said rotary member and thereby timing the selector conditioning operations during each signal period and for 55 arresting said rotary member at the end of each signal.

35. A telegraph receiver responsive to signals formed of two different electrical conditions extending as described through starting, selecting and spacing time intervals, and comprising a set of selectors, an electro-magnet, a rotary, power-driven start-stop member adapted to be continuously advanced in definite timed relation with the selecting 60 intervals of the received signals, means me-

chanically controlled by the armature of said magnet in response to the starting and spacing intervals respectively to initiate and arrest the operation of said member and means 70 mechanically actuated by said member and mechanically controlled by the armature of said magnet in response to the selecting intervals of the signals for conditioning said 75 selectors, one at a time, in different combinations.

36. In receiving apparatus for start-stop selecting telegraphs, a set of selectors, a common selector actuator, a rotary member for moving said actuator past said selectors in succession, said actuator being shiftable 80 at an angle to its path of movement to position said selectors, one at a time, in different combinations, a motor-driven, start-stop means for continuously advancing and locally timing the operation of said rotatable member during each complete selecting 85 operation and to arrest the same at the end of such operation, and an electro-magnet responsive to received signals for tripping said motor-driven means into operation at 90 the beginning of each signal and thereafter selectively controlling the selector setting movements of said actuator.

37. In a receiving apparatus for start-stop telegraphs, a set of selectors operable 95 in different combinations, a common selector actuator, a rotary member for moving said actuator past said selectors in succession, a cam having spaced operating portions and cooperating with said rotary member to 100 shift said actuator transversely of its path of movement to set said selectors one at a time, and an electro-magnet responsive to received signals and having an armature mechanically controlling the selector setting 105 movements of said actuator.

38. In a selector mechanism for telegraphs, a plurality of selectors, a common, rotatable and axially movable member for operating said selectors and a single magnet 110 controlling the rotary and axial movements of said member to thereby variably position said selectors in different combinations.

39. In a receiving apparatus for start-stop printing telegraphs, a set of selectors operable in different combinations, a common selector actuator, a start-stop rotary member for moving said actuator past said selectors in succession, said actuator being shiftable transversely to its path of movement to set said selectors one at a time, an operating motor for said rotary member, an electro-magnet responsive to received signals for initiating the operation of said rotary member and thereafter selectively controlling the selector setting movements of 115 said actuator and a printer mechanically controlled by said selectors and said rotary member and operated by said motor.

40. A printing telegraph receiver respon- 120

sive to signals consisting of two different electrical conditions extending through separate starting, selecting and spacing time intervals, and comprising a set of permutation selectors, an actuating member adapted, by its movement through a series of uniformly spaced positions, to mechanically set said selectors one at a time, start-stop means locally controlled when in operation, for moving said actuating member through the said positions in timed relation with the selecting intervals of the signals and for arresting the same in a relatively adjustable normal position, a printer mechanically controlled by said selectors and said start-stop means, electro-magnetic means normally energized by the spacing conditions, for initiating the operation of said start-stop means in response to the starting conditions and a member electromagnetically vibrated for mechanically controlling the selector setting operations of said actuating member in accordance with the character of the selecting conditions.

41. In combination in a telegraph receiver, a single selecting magnet responsive to received signals, a set of permutation selectors, a rotary actuating member, start-stop means initiated in operation by said magnet, for rotating said actuator under local control through a series of uniformly spaced angular positions during each signal period and for arresting the same in an angularly adjustable stopped position, means actuated and selectively controlled by the rotation of said member and the position of the magnet armature respectively and operative, in the different uniformly spaced positions of said member, to effect the setting of said selectors in different combinations without tending to change the selecting position of the magnet armature.

42. A printing telegraph receiver comprising normally energized electro-magnetic means responsive to code combinations of selecting conditions each preceded by a starting condition, a controlling member vibrated thereby, a set of permutation selectors, a start-stop actuating shaft rotatable relatively to said selectors, means, initiated in operation by said electro-magnetic means in response to the starting conditions, for rotating said shaft under local control through a series of uniformly spaced, angular positions in timed relation with the selecting conditions of each code combination, means mechanically actuated and controlled by the rotation of said shaft and the position of said vibrating member respectively and operative, in the different uniformly spaced positions of said shaft, to set said selectors in different combinations, means for effecting a relative angular adjustment between the selector operating and the stopped positions of said shaft and a

printer mechanically controlled by said selectors and said shaft.

43. A printing telegraph receiver comprising a set of permutation selectors, a rotatable actuating member, start-stop means for continuously rotating said actuating member through a series of uniformly spaced angular positions during each setting cycle and for arresting the same in an angularly adjustable normal position, means mechanically actuated by the rotation of said member and operative, in the different uniformly spaced positions thereof, for setting said selectors one at a time, a printer mechanism mechanically controlled by said selectors and said start-stop means, a vibrating member for mechanically and variably controlling the operation of said selector-setting means and electro-magnetic means responsive to received signals for initiating the rotation of said actuating member and for operating said vibrating member.

44. A printing telegraph receiver responsive to signals consisting of code combinations of selecting conditions each preceded and followed by starting and spacing conditions respectively, a set of mechanical permutation selectors, a start-stop rotary actuating member, a motor and an interposed clutch for continuously rotating said member in timed relation with the selecting conditions of each code combination, stop devices for arresting the rotation of said member in an angularly adjustable normal position, means actuated by said member in different uniformly spaced angular positions thereof for setting said selectors one at a time, a printer mechanically controlled by said selectors, a single selecting magnet normally energized by the spacing conditions, and an armature lever operated by said magnet for releasing said stop devices and for mechanically controlling the selector setting operations in response to the starting and selecting conditions respectively.

45. A selector mechanism for telegraph receivers comprising a single selecting magnet responsive to signals formed of two different conditions extending through separate starting, selecting and spacing time intervals, a set of selectors, an actuating shaft, means mechanically actuated by the rotation of said shaft and mechanically controlled by the armature of said magnet during the selecting intervals and effective in the normal position of said armature for setting said selectors one at a time, and means controlled by the magnet armature for initiating and arresting the rotation of said shaft in response to the off-normal and normal positioning of the armature by the starting and spacing conditions respectively.

46. A receiver selector comprising a single normally energized, controlling magnet, a shaft and means for rotating said shaft,

- means controlled by the de-energization of said magnet for initiating the rotation of said shaft and by the energization thereof for arresting the shaft, a set of selectors, 5 means actuated by the rotation of said shaft for successively setting said selectors and a member vibrated by said magnet and operative, upon the de-energization thereof, to interfere with the setting of said selectors by 10 said shaft-actuated means.
47. A receiving selector comprising a single selecting magnet, a cooperating shaft, means for rotating said shaft, means controlled by the de-energization of said magnet 15 for initiating the rotation of said shaft at the beginning of each signal period and by the energization thereof for arresting the shaft at the end of such period, a plurality of selectors and selector-setting means actuated by the rotation of said shaft and effective upon the energization of the magnet to cause relative selective positioning of said 20 selectors.
48. A receiver mechanism for telegraphs 25 selectively responsive to signals consisting of combinations of two different conditions, and comprising a shaft, means for effecting and locally timing the rotation of said shaft in definite relation with the received conditions, 30 a set of selectors, means actuated by the rotation of said shaft and operative to mechanically and successively move said selectors, a member electro-magnetically vibrated in response to the received conditions and 35 adapted to permit movement of said selectors by said shaft-actuated means or to mechanically prevent any substantial movement thereof, and means controlled by said vibrating member for initiating and arresting the 40 rotation of said shaft at the beginning and end respectively of each signal.
49. A printing telegraph receiver comprising a set of relatively movable selectors, a common actuator therefor, means, locally actuated and timed in operation, for advancing said actuator in one direction into operative relation with said selectors in order and also for reciprocating same in a transverse direction to position said selectors and a 45 single selecting magnet responsive to received current impulses for variably controlling the transverse reciprocating movements of said actuator.
50. In a printing telegraph receiver responsive to combinations of two different conditions extending through separate starting and selecting time intervals, a set of selectors, a common selector actuator, a start-stop rotatable shaft for moving said actuator 50 in one direction into operative relation with said selectors successively and in timed relation with the selecting intervals, a cam having a circular series of uniformly spaced, offset portions cooperating with said shaft to 55 reciprocate said actuator in a transverse di- rection to set said selectors one at a time and during the mid-portions only of the selecting intervals and electro-magnetic means for initiating the rotation of said shaft in response to the starting conditions and for 70 variably controlling the reciprocating movements of said actuator in accordance with the selecting conditions.
51. A telegraph receiver comprising a set of relatively movable selectors, a common actuator therefor, a start-stop rotatable shaft for effecting and locally timing the movement of said actuator in one direction into operative relation with said selectors in order, means actuated by the rotation of said 75 shaft and operative in different angularly spaced positions thereof for reciprocating said actuator in a transverse direction to thereby position said selectors one at a time, and a single selecting magnet responsive to 80 received current impulses for initiating the rotation of said shaft and thereafter variably controlling the reciprocating movements of said actuator.
52. In a telegraph receiver, a set of selecting elements operable in different combinations in accordance with the received signals, actuating means movable in two directions substantially at right angles to operate said elements one at a time, means for 85 effecting and locally timing the movements of said actuating means in both such directions and a magnet responsive to the received signals and having an armature mechanically controlling the movement of said 90 actuating means in one such direction to thereby variably determine the operation of said selecting elements.
53. In a telegraph receiver, a set of selecting elements operable in different combinations in accordance with the received signals, actuating means therefor, a rotatable shaft movable through a series of uniformly and angularly spaced positions to thereby associate said actuating means with 95 said selectors in order, spring and cam means controlled by the rotation of said shaft for shifting said actuating means into and out of position to operate said selecting elements, and a member electro-magnetically vibrated in response to received signals for 100 permitting or blocking the operation of said spring means.
54. A telegraph receiver comprising a set of selecting elements operable in different 105 combinations, a common selector actuator adapted to be advanced in one direction and reciprocated in transverse direction and thereby moved through a series of uniformly spaced selector operating positions, a motor-driven start-stop shaft adapted to be continuously rotated during each signal period to thereby effect the advance movement of said actuator and locally time its selector-setting 115 operations, stop devices for arresting said 120 operations, stop devices for arresting said 125 operations, stop devices for arresting said 130

- shaft at the end of each signal, a vibrating member for mechanically and variably controlling the reciprocating movements of said actuator and electro-magnetic means responsive to received signals for tripping said stop device and for actuating said vibrating member.
55. A telegraph receiver comprising a set of mechanical selecting elements, a start-stop 10 rotary actuating member for mechanically operating said elements in different combinations, said member being rotatable and also axially shiftable into operative relation with said selecting elements in order, means 15 for uniformly effecting the rotation of said actuator under local control during each signal period and for arresting the same in a normal stopped position that is angularly adjustable to and from said selecting elements, a vibrating member for mechanically and selectively controlling the axial movements of said rotatable actuating member and electro-magnet means responsive to received signals for initiating the rotation of 20 said actuating member and for operating said vibrating member.
56. A telegraph receiver comprising a set of relatively movable selectors, a rotary operating member, a motor and an interposed 25 clutch for continuously rotating said member during each signal period, stop devices for arresting the same in a normal position at the end of such period, a cam having a circular series of uniformly spaced offset 30 portions cooperating with said member to effect the setting of said selectors one at a time and during portions only of the selecting intervals of the signals, a single selecting magnet responsive to received signals 35 for tripping said stop devices and for subsequently controlling the selector setting operations, and means for angularly adjusting the normal stopped position of said rotary member.
57. In combination in a start-stop printing telegraph system, rotary transmitter and receiver members, means controlled by the rotary movement of the transmitter member during each signal period for establishing two different line conditions extending through separate starting and selecting time intervals and for holding the line closed during spacing intervals between the signals, a normally energized receiver magnet responsive to line conditions, a set of selectors 50 under the joint mechanical control of said receiver member and the armature of said magnet and positioned thereby one at a time in different combinations, start-stop means 55 for rotating said transmitter and receiver members under local control during each signal period, each through a series of uniformly spaced operating positions, and for arresting the same in normal position, the 60 receiver start-stop means being initiated in 65 operation by said magnet in response to the starting conditions, means for controlling the transmitter start-stop means independently of the line conditions, and means for angularly adjusting the normal stopped position of the rotatable receiver member.
58. A station equipment for printing telegraphs comprising corresponding sets of transmitting and receiving selectors, transmitter and receiver actuator shafts, an operating motor and separate interposed clutches for continuously advancing said shafts through a series of operating positions during each signal period, stop devices for arresting said shafts, means actuated by the movement of the transmitter shaft and controlled by the transmitting selectors for imparting separate starting and selecting conditions to the line and for maintaining the line in closed condition during spacing intervals between the signals, means mechanically actuated by the rotation of the receiver shaft for operating the receiver selectors one at a time, a printer mechanically controlled by the receiving selectors and 75 shaft, a single selecting magnet for releasing the receiver stop devices and for subsequently controlling the operation of said selector setting means in response to the starting and selecting conditions respectively, and means, wholly mechanical, for controlling the transmitter stop devices and 80 selectors.
59. A station equipment for start-stop printing telegraphs, comprising a set of permutation selectors, a printer mechanically controlled thereby, a common rotary actuating member for said selectors having an angularly adjustable, normal position of rest, a rotatable transmitter member having a normal position of rest, separate motor-driven start-stop clutches for continuously rotating said members, each through a series of uniformly spaced operating positions, stop devices for arresting the same in their 90 normal positions, means actuated by the rotation of said transmitter member for imparting separate starting and selecting conditions to the line and for holding the line closed during spacing intervals between signals, a normally energized selecting magnet having an armature for mechanically tripping said receiver stop devices and for mechanically controlling the selector-setting operations of the receiver actuator in response to the starting and selecting line conditions respectively and means independent of said magnet for controlling the transmitter stop devices.
60. A printing telegraph receiver comprising a magnet responsive to code combinations of selecting conditions each preceded by a starting condition, a set of permutation selectors, a relatively rotatable, actuating member for said selectors, a motor 100 105 110 115 120 125
- 65 receiver start-stop means being initiated in 130

- driven start-stop shaft, initiated in operation by said magnet in response to the starting conditions, for continuously rotating said member through a series of uniformly spaced 5 positions in timed relation with the selecting conditions of each code combination and for arresting the same in a relatively adjustable, stopped position, means mechanically actuated and timed by the rotation of said member and selectively controlled by the position of the armature of said magnet and operative, in the different uniformly spaced 10 positions of said actuating member, to set said selectors one at a time in different combinations, and a printer mechanically controlled by said selectors and said start-stop shaft.
61. A printing telegraph receiver comprising a set of primary selectors, a relatively 15 rotatable selector actuating member, motor-driven start-stop means for continuously advancing said actuating member through a series of uniformly spaced selector operating 20 positions during each signal period and for arresting the same in a relatively adjustable, stopped position, a printer mechanism having a second set of selectors controlled by 25 said primary selectors and said motor-driven start-stop means in a manner permitting the overlapping of the character selecting and printing operations, and a single selecting magnet responsive to received signals for initiating the operation of said start-stop means and for subsequently controlling the 30 operation of said selector actuator.
62. A printing telegraph receiver comprising a set of primary selectors, a relatively rotatable, start-stop actuating shaft continuously motor-driven during each 35 signal period, means mechanically actuated by the rotation of said shaft and operative in different uniformly spaced angular positions thereof for setting said selectors one at a time, a printer mechanism having a second 40 set of selectors, means actuated by said start-stop shaft for successively restoring said printer selectors, transferring the setting of said primary selectors to the printer 45 selectors and restoring said primary selectors for further operation, and a single selecting magnet responsive to received signals for initiating the rotation of said shaft and for subsequently controlling the selector 50 setting operations of said shaft actuated means.
63. A printing telegraph receiver comprising a set of primary selectors, a relatively rotatable, start-stop actuating shaft continuously motor-driven during each 55 signal period, means mechanically actuated by the rotation of said shaft and operative in different uniformly spaced angular positions thereof for setting said selectors one at a time, a printer mechanism having a second 60 set of selectors, cams on said shaft for successively restoring said printer selectors, transferring the setting of said primary selectors to the printer 65 selectors and restoring said primary selectors for further operation, and a single selecting magnet responsive to received signals for initiating the rotation of said shaft and for subsequently controlling the selector setting operations of said shaft actuated means.
64. In a combined printing telegraph transmitter and receiver, the combination of transmitter contacts, a set of mechanical controlling selectors therefor, key levers for positioning said selectors in different combinations, a cam shaft for actuating said contacts in accordance with the setting of said selectors, a printer, cooperating sets of primary and secondary selectors for controlling the printer, a rotary actuator for positioning said primary selectors, a power shaft for operating said actuator and said printer, a magnet responsive to impulses from said contacts for controlling the selector positioning operations of said actuator and a common motor and separate interposed start-stop clutches for driving said shafts.
65. In a combined printing telegraph transmitter and receiver, the combination of transmitter contacts, a set of mechanical controlling selectors therefor, key levers for positioning said selectors in different combinations, a cam shaft for actuating said contacts in accordance with the setting of said selectors, a printer, cooperating sets of primary and secondary selectors for controlling the printer, a rotary actuator for positioning said primary selectors, a power shaft for operating said actuator and said printer, a magnet responsive to impulses from said contacts for controlling the selector positioning operations of said actuator, a common motor and separate interposed clutches for driving said shafts and individual clutch controlling devices independently actuated by said key levers and said magnet respectively.
66. In a combined printing telegraph transmitting and receiving apparatus, the combination of transmitter contacts, a cam shaft having successively acting sections for actuating said contacts to transmit starting, selecting and spacing conditions, a set of mechanical selectors for determining the selecting conditions, a plurality of key levers for positioning said selectors in different combinations, a printer, sets of cooperating primary and secondary printer controlling selectors, an actuator for mechanically positioning said primary selectors one at a time, a power shaft for operating said selector actuator and said printer, a magnet responsive to impulses from said contacts and also to received signals for controlling the operation of said selector actuator and a

- common motor and separate interposed start-stop clutches, independently controlled by said key levers and said magnet respectively, for actuating said shafts.
- 5 67. In a telegraph system, the combination with a normally closed line circuit connecting two or more stations, sets of transmitter contacts and receiver magnets interposed in series in said line circuit, motor driven start-stop actuating and timing shafts and corresponding sets of mechanical permutation selectors individual to said sets of transmitter contacts and said magnets respectively, means, wholly mechanical, for 15 setting said transmitting selectors in different combinations and for starting said transmitter shafts, means actuated by the movement from normal of said transmitter shafts for operating the corresponding contacts to impart to the line circuit, starting conditions followed by selecting conditions in accordance with the setting of the corresponding selectors, means mechanically actuated by the armature of said magnet 25 for starting the corresponding receiver shafts in response to the starting conditions, means mechanically actuated and controlled by the receiver shafts and the armatures of said magnets respectively for positioning 30 the corresponding sets of selectors in different combinations in accordance with the selecting conditions, and recorders mechanically controlled by the receiver selectors and shafts.
- 35 68. In a telegraph receiver, a set of relatively movable permutation selectors and means for setting said selectors in different combinations, comprising a common vibratory member for mechanically controlling 40 the setting of said selectors, a rotary member operative in a series of uniformly spaced angular positions to mechanically set said selectors one at a time in accordance with the position of said vibratory member, start- 45 stop means for continuously advancing said rotary member through its selector setting positions and for arresting the same in a relatively adjustable normal position and electro-magnetic means responsive to received signals for initiating the operation of 50 said rotary member and for actuating said vibratory member.
69. In a printing telegraph receiver, a single selecting magnet responsive to received code combinations of impulses, a rotating shaft arranged to be variably operated under control of said magnet and according to the received impulses, and selectors selectively positioned by said shaft.
- 55 70. In a printing telegraph receiver, a selecting magnet responsive to received combinations of impulses a rotatable shaft shiftable longitudinally under control of said magnet, and selectors selectively positioned 60 in accordance with the longitudinal movements of said shaft.
71. In a printing telegraph receiver, a magnet responsive to received code combinations of impulses, a plurality of selectors, a member actuated by said shaft into association with said selectors successively, and means controlled by said magnet for selectively permitting said member to actuate 65 said selectors.
72. In a printing telegraph receiver, a magnet responsive to received code combinations of impulses, a start-stop rotating shaft, a plurality of selectors and a common member under the joint mechanical control of said shaft and the armature of said magnet for selectively positioning said selectors.
73. In combination in a start-stop telegraph apparatus, rotary transmitter and receiver members, means controlled by the transmitter member for establishing line conditions, a vibrating member responsive to line conditions, a set of permutation selectors under the joint mechanical control of said vibrating member and said rotary receiver member, start-stop means for rotating 80 said transmitter and receiver members and for arresting the same in their normal positions, the receiver start-stop means being initiated in response to starting line conditions, and means wholly mechanical for controlling the transmitter start-stop means independently of the line conditions.
74. In a start-stop telegraph apparatus, a receiver shaft, a transmitter shaft, a wholly mechanical code transmitter for establishing 100 line conditions controlled by said transmitter shaft, a single electro-magnet responsive to line conditions, a set of permutation selectors under the joint mechanical control of said receiver shaft and the armature of said magnet, a common motor and separate clutches for operating said transmitter and receiver shafts, the receiver clutch being under control of said electro-magnet and independent means for controlling the transmitter clutch.
75. In a telegraph receiver, a magnet responsive to received impulses, a set of permutation selectors, a rotating selector actuator controlled by said magnet, a type wheel 115 controlled by said selectors, and a common power-driven start-stop clutch for rotating said actuator and said type wheel and for arresting the same in normal position at the end of each signal, said magnet being responsive to received signals for tripping said clutch.
76. In a telegraph receiver, a magnet responsive to received impulses, a type wheel selectively operated by said magnet, and a 120 start-stop shaft carrying said type wheel having a normal position of rest, said shaft being arranged to start from its normal position.

sition in response to a received impulse and rotate continuously until the normal position is again reached.

77. In a telegraph receiver, a magnet responsive to received impulses of uniform length, selector members, a rotating actuator controlled by said magnet for setting said selectors successively and in timed relation with the received impulses and means for adjusting the angular position of said actuator.

78. In a printing telegraph receiver responsive to received impulses of uniform length, a set of selectors, a rotatable actuator operated in response to received impulses for

mechanically and successively operating said selectors in timed relation with the received impulses, start-stop means for rotating said actuator and means for adjusting the normal stopped position of said actuator.

79. In a printing telegraph receiver, a start-stop shaft, a normally energized magnet, means responsive to the de-energization of said magnet for releasing said shaft for rotation, and selector means operated by said rotating shaft in response to the energization of said magnet.

CHARLES L. KRUM.
HOWARD L. KRUM.

CERTIFICATE OF CORRECTION.

Patent No. 1,635,486.

Granted July 12, 1927, to

CHARLES L. KRUM ET AL.

It is hereby certified that error appears in the printed specification of the above numbered patent, requiring correction as follows: page 6, line 17, for the word "fixed" read "flexed"; page 7, lines 97 to 99, strike out the words "To in- with the proper operation of the" and insert instead "To insure the stopping of the rotary"; page 8, line 34, after the word "initial" insert the word "or"; page 11, line 31, for "Fig. 2" read "Fig. 22"; page 14, line 51, claim 26, after the word "by" insert the word "said"; page 18, line 23, claim 55, for the word "electro-magnet" read "electro-magnetic"; and that the said Letters Patent should be read with these corrections therein that the same may conform to the record of the case in the Patent Office.

Signed and sealed this 4th day of October, A. D. 1927.

Seal.

M. J. Moore,
Acting Commissioner of Patents.
